UNITED STATES PATENT OFFICE.

ARTHUR R. MOSLER, OF NEW YORK, N. Y.

ELECTRIC IGNITION DEVICE.

SPECIFICATION forming part of Letters Patent No. 738,831, dated September 15, 1903.

Application filed September 25, 1902. Serial No. 124,746. (No model.)

To all whom it may concern:

Be it known that I, ARTHUR R. MOSLER, a citizen of the United States, and a resident of the borough of Manhattan, in the city and State of New York, have invented a new and useful Improvement in Electric Ignition Devices, of which the following is a specification.

My invention relates to an improvement in electric ignition devices, and has for its object to provide certain improvements in the construction, form, and arrangement of the several parts of an electric ignition device whereby the liability of misfiring is materially reduced and in which the conducting-wire may be adjusted longitudinally for bringing its sparking-point into proper relation with respect to the sparking-point of the hollow base without affecting the assembling of the several parts.

A further object is to provide a device in which the insulating-block is made reversible, so as to lengthen its life.

A still further object is to provide a protector for the outer end of the insulating-block.

A practical embodiment of my invention is represented in the accompanying drawings, in which—

Figure 1 is a view in side elevation of the electric ignition device. Fig. 2 is a longitudinal central section through the same, showing the device in engagement with the cylinder-wall of an engine of such diameter that the inner end of the base projects into the interior of the cylinder. Fig. 3 is a view in side elevation of the insulating-block. Fig. 4 is an end view of the same. Fig. 5 is a side view of one of the packing rings or gaskets which are interposed between the insulating-block and base and cap of the device. Fig. 6 is a transverse central section through the ring or gasket, and Fig. 7 is a face view of the same.

The conducting-wire is denoted by 1, and it may be provided at its inner end with the usual platinum point 2. This conducting-wire 1 is exteriorly screw-threaded.

A reversible insulating-block surrounds the conducting-wire 1 for a considerable portion of its length, which block comprises reduced tubular end portions 3 and 4 and an

enlarged middle portion 5. Annular shoulders 6 and 7 are thus formed around the periphery of the insulating-block.

Corresponding holes 8 and 9 extend inwardly from the opposite ends of the insulating-block, which holes preferably flare outwardly toward the ends of the block.

Angular seats 10 and 11 are provided at the inner ends of the holes 8 and 9.

A hole 12 connects the holes 8 and 9 for permitting the insertion of the conducting-wire through the block.

A shoulder-nut 13 has a screw-threaded engagement with the inner portion of the conducting-wire 1, which nut is locked against movement in the inner end of the insulating-block—in the present instance the seat 10 at the inner end of the hole 8.

A hollow base 14 embraces the middle and inner end portion of the insulating-block, which base is provided with a shoulder 15, between which and the shoulder 6 of the insulating-block I insert one of my improved packing rings or gaskets, to be hereinafter more fully described.

A cap 16 embraces the insulating-block and has a screw-threaded engagement with the outer end of the base, which cap is provided with an annular shoulder 17, between which and the shoulder 7 of the insulating-block I insert one of my improved packing rings or gaskets.

The base 14 is provided with a reduced closed hollow shank 18, having a small opening 20, which in the present instance is located in the end 19 thereof. The walls of this opening 20 through the inner end of the base 14 may be beveled, so as to present a sharp edge for assisting the jump of the spark from the sparking-point 2 to the walls of the said opening 20. This end 19 of the hollow shank 18 of the base is spaced a short distance from the inner end of the insulating-block, and the side walls of the shank are closed, so as to form a chamber surrounding the contact-point with the only exit therefrom through the opening 20 in the end wall of the base. By this arrangement a closed chamber is formed around the sparking-point 2, irrespective of the thickness of the cylinder-wall of the engine to which the ignition device is attached. This is very important,

for the reason that it enables the small quantity of gas which enters the said chamber to be first ignited even by a very slight spark, and this ignited gas bursts through the small opening 20 into the interior of the cylinder, thus igniting the larger mass of gas therein.

The portion of the insulating-block which projects outwardly beyond the cap 16 is protected from being injured and broken by means of an annular protector 21 of some suitable material—such, for instance, as hard fiber or mica. The inner end of this protector engages the cap 16 and the outer end preferably projects beyond the outer end of the insulating-block. This protector is held in position by means of a nut 22, having a screw-threaded engagement with the conducting-wire 1, between which nut and the outer end of the protector I may insert a suitable bearing-washer 23. The usual binding-nut 24 is also engaged with the outer end of the conducting-wire 1.

The packing rings or gaskets which I interpose between the enlarged portion 5 of the insulating-block and the base and cap, respectively, are constructed as follows: A shell of thin sheet metal is bent to form an inner wall 25 and two outwardly-extended side walls 26 27, spaced a short distance apart. A yielding packing 28—such, for instance, as asbestos fiber—is inserted in the annular groove formed by the walls 26 27 of the ring or gasket preferably by winding the fiber around the gasket within the said groove. These gaskets thus formed are inserted in position within the ignition device, and when they become worn or damaged they may be readily replaced by other gaskets of the same construction in a very simple and expeditious manner.

It has been found that the use of asbestos gaskets is defective, inasmuch as they will not hold tightly against the explosive pressure of the gases unless the parts are screwed very tightly together. The screwing down of this asbestos material renders it practically impossible to remove the point without breaking the same. Furthermore, these gaskets become more or less disintegrated by the constant jar to which the ignition device is subjected. All this is obviated by the use of the gasket hereinabove described.

It will be seen that in the ignition device constructed as above described the conducting-wire 1 may be turned in one direction or another in accurately adjusting its sparking-point with respect to the base which forms the other sparking-point so as to produce the best results. The end walls of the insulating-block are also made of such form as to produce the best preventive of short-circuiting by the deposit of carbon should oil be used in excess or

an extra rich mixture of hydrocarbon gas or air find its way into the small chamber of the plug. Furthermore, the block is so constructed that it may be quickly reversed when desired to bring its other end into the interior of the base. When in use, the insulating-block becomes extremely hot, and it has been found that the block is frequently cracked or broken by the exposure of the outer ends to the elements—such, for instance, as rain, snow, &c. This heretofore-exposed end is now protected, as above described, not only from the elements, but also from accidental blows of moderate strength.

What I claim is—

1. An electric ignition device comprising a hollow base, a cap engaging the same, an insulating-block secured within the base and cap and projecting beyond the cap, a conducting-wire within the block, a protector surrounding the exposed portion of the said block and means engaging the conducting-wire for forcing the protector against the cap and securing it in position around the block. 85
2. An electric ignition device comprising a hollow base, a cap therefor, a single reversible insulating-block secured within the base and cap and a conducting-wire extending through the said block. 90
3. An insulating-block for electric ignition devices comprising an enlarged middle portion and reduced hollow end portions having angular seats therein. 95
4. A reversible block for electric ignition devices comprising an enlarged middle portion and reduced end portions having holes extending inwardly toward the enlarged middle portion and angular seats at the inner ends of the said holes. 100
5. An insulating-block for electric ignition devices having an enlarged portion and a reduced end portion having a hole extended inwardly toward the enlarged portion, the walls of the hole being made flaring. 105
6. An insulating-block for electric ignition devices having a hole therethrough and an angular seat surrounding the hole intermediate the ends of the block. 110
7. A packing-ring for electric ignition devices comprising a shell bent to form lateral walls and a longitudinal wall connecting the same, and a filling of packing material in the space thus formed. 115

In testimony that I claim the foregoing as my invention I have signed my name, in presence of two witnesses, this 19th day of September, 1902.

ARTHUR R. MOSLER.
